(57) CLAIM

The ornamental design for a baseball bracelet, as shown and described.

DESCRIPTION

FIG. 1 is a side elevational view of the baseball bracelet of the invention;

FIG. 2 is a top plan view thereof;

FIG. 3 is a bottom plan view thereof;

FIG. 4 is an end elevational view thereof, the opposite end view being a mirror image;

FIG. 5 is a top, right perspective view thereof; and,

FIG. 6 is a top view illustrating the baseball bracelet of the invention as being worn on the arm of a user. The broken lines represent the arm of the user and form no part of the invention.
